UNITED STATES PATENT OFFICE

HARRISON ANDERSON, OF LOS ANGELES, CALIFORNIA

BOOKHOLDER

Application filed June 15, 1929. Serial No. 371,275.

My invention relates to bookholders, and it has for a purpose the provision of a bookholder particularly adapted for holding a book upon or in close proximity to a desk or other horizontal support and in closed and open positions, the holder in its association with a desk functioning to support the book in open position on top of the desk, and when not in use in closed position at one side of the desk.

It is also a purpose of my invention to provide a bookholder having a book holding frame, the parts of which are movable relatively to permit the frame to occupy open and closed positions, and wherein the frame is provided with a simple and effective means for detachably securing a book within the frame in such manner that it may be readily and quickly removed from the frame to permit the substitution of another book.

A further purpose of my invention is the provision of a bookholder wherein the book holding frame is adjustable to accommodate books of different sizes, and to effectively hold such books in any position of adjustment of the frame.

I will describe only one form of bookholder embodying my invention, and will then point out the novel features thereof in claims.

In the accompanying drawings:

Fig. 1 is a view showing in top plan one form of bookholder embodying my invention wherein the frame of the bookholder is in lowered and closed position, and in applied position to a desk.

Fig. 2 is a view showing the bookholder in front elevation and elevated and open, and in applied position to the desk.

Fig. 3 is a view showing the bookholder in side elevation and elevated and open.

Fig. 4 is a sectional view taken on the line 4-4 of Fig. 1.

Fig. 5 is a view similar to Fig. 2 showing the bookholder in lowered and folded position.

In carrying out my invention, I provide a bookholder which is more particularly adapted for association with a desk or similar form of office furniture for the holding of a book

in open position on the top of the desk, as illustrated in Fig. 2, and when not in use in closed position at one side of the desk as illustrated in Figs. 1 and 5. As illustrated to advantage in Figs. 2 and 3, a support 15 of wood or other suitable material is secured by screws 16 or in any other suitable manner to the side of a desk indicated at 17, the support being co-extensive in height with the desk so that its lower end is in contact with the floor, while its upper end is flush with the top of the desk. Upon this support is mounted a book holding frame comprising a bottom leaf or section 18 and a back leaf or section 19. The bottom leaf is preferably in the form of a metal plate of rectangular shape, while the back leaf is made up of a pair of plates or sections 20 and 21 extensibly connected to increase or decrease the overall length of the back leaf for the accommodation of books of different sizes. In the present instance the plate 20 is provided with a pair of slots 23 through which bolts 24 extend. These bolts are extended through the plate 21, and are provided with nuts and washers 25 and 26 for securing the bolts against movement within the slots so as to maintain any position of adjustment of the plates with respect to each other.

The bottom leaf is mounted on the support 15 by a pair of hinged members 27 and 28, the lower leaves of which are secured by screws to the support, while the upper leaves are formed with angular extensions 29 bolted or otherwise secured to the bottom leaf 18. The back leaf 19 is associated with the bottom leaf 18 to form the holding frame by means of hinged members 30 and 31 having the lower leaves secured to the upper leaves of the hinged members 27 and 28, respectively, while the upper leaves are secured to the back leaf by bolts 32 extending through slots 33 and 34 in the plates 20 and 21, and the upper leaves, respectively. These slots 33 and 34 are disposed at right angles to each other so that by loosening the bolts, longitudinal and lateral adjustment of the plates on the hinge members may be effected in addition to the longitudinal adjustment of the plates themselves.

From the foregoing construction, it will be clear that the hinge members 27 and 28 support the bottom leaf 18 on the support 15 to allow the leaf to occupy the lower position shown in Fig. 5 or the elevated position shown in Fig. 2, while the hinge members 30 and 31 permit swinging movement of the back leaf 19 in respect to the bottom leaf 18 in order to allow the frame to occupy open and closed positions. The hinge members 27 and 28 are disposed one above the other in order to support the book holding frame in a position inclined with respect to the horizontal so that when the frame is in the elevated position illustrated in Figs. 2 and 3, a book supported on the frame will be inclined to facilitate reading.

The bottom leaf 18 is supported in elevated position by means of an arm 35 consisting of two parts hingedly connected to each other and to the bottom leaf and support 15. The parts of the arm are adapted to be releasably retained in longitudinally aligned position by means of a spring 36 and, by the provision of a lever 37, the arm may be broken to allow folding of the parts to permit movement of the bottom leaf to lowered position. The construction of the arm 35 forms no part of the present invention as it is embodied in my Patent No. 1,842,954, dated January 26, 1932.

For retaining a book within the holding frame and securely to the back leaf 19, and in such manner as to permit the ready attachment and detachment thereof, I provide flanges 38 and 39 upon the opposite ends of the back leaf 19. These flanges may be formed by extending and bending the ends of the back leaf, as will be understood. The lower flange 39 is provided at its inner side with a set of relatively pointed prongs 40 which are adapted to be extended between the leaves of a book. The upper flange 38 is recessed as indicated at 41 to accommodate a part of a bracket 42 provided with a head 43 disposed at the inner side of the flange and having a set of prongs 44 thereon which are adapted to extend between the leaves of a book and to co-operate with the other set of prongs 40 for securing the book within the frame and against the back leaf 19. The bracket 42 is removable from the flange 38 in order to permit application and removal of a book to and from the back leaf. For securing the bracket in fixed position on the flange 38, I provide a cam lever 45 pivoted on the bracket so as to be movable to engage or disengage the flange 38 and when in engagement therewith to exert an outward pull on the bracket for maintaining the head 43 contiguous with the inner side of the flange 38. When the lever 45 is moved to a position in which its cams are free of the flange 38, it will be understood that the bracket together with its prongs can be readily disengaged

from the flange to allow removal of the book from the frame. To prevent twisting movement of the head 43, the upper edge of the flange 38 is lipped as indicated at 38a.

In the lowered position of the book holding frame, the bottom leaf 18 abuts a yoke 46 secured to the support 15 in order that the frame may occupy a vertical position and to relieve the hinge members of any undue stress or strain. In moving the frame to lowered position, which movement may be effected by a folding of the arm 35, the leaf 18 engages a spring 47 secured to the support 15 so that if the leaf is accidentally released and the frame as a consequence dropped, the spring will function as a cushion to retard downward movement of the frame and thus prevent the leaf 18 from striking the yoke 46, with a force sufficient to damage the parts of the holder.

Although I have herein shown and described only one form of bookholder embodying my invention, it is to be understood that various changes and modifications may be made herein without departing from the spirit of the invention and the spirit and scope of the appended claims.

I claim:

1. A bookholder, comprising a book holding frame having a bottom leaf and a back leaf hingedly connected to occupy open and closed positions, means for so mounting the frame on a desk that when said leaves are in open position the bottom leaf can project to one side of the desk while the back leaf reposes on the desk and co-acts with the bottom leaf to support an opened book in a position for reading by an occupant of the desk, and when in closed position said leaves can be moved to occupy vertical positions at one side of the desk, and foldable means for supporting the bottom leaf horizontally when in open position.

2. A bookholder comprising a support adapted to be secured to a desk, a book holding frame, hinged members secured to the support and to the frame so as to permit the frame to be movable to occupy a lowered position at one side of the support and an elevated position above the support, said frame having bottom and back leaves movable to occupy open and closed positions, means for detachably securing a book within the frame, and foldable means for supporting the frame in elevated position, the back leaf being disposed to overlie and rest upon the desk when the leaves occupy open position and the frame occupies elevated position.

3. In a bookholder, a frame having a back leaf, two sets of prongs on the back leaf one of which is removable, and means for securing said removable set of prongs to the back leaf so as to coact with the other set in detachably securing a book to the back leaf, said means including a cam manually operable to engage

the back leaf and secure the corresponding set of prongs against removal from the back leaf.

4. A bookholder, comprising a frame having parts relatively movable to permit opening and closing of the frame, means secured to the frame for supporting the latter so that it is movable to occupy elevated and lowered positions, and resilient means interposed in the path of movement of the frame for cushioning movement of the latter to lowered position, said resilient means comprising leaf springs, and a yoke for defining the lowered position of the frame, said springs being interposed between the frame and the yoke and adjacent the yoke.

HARRISON ANDERSON.
